HATCH PLUGS

Carl F. Massopust, Highland Park, Ill., assignor to General American Transportation Corporation, Chicago, Ill., a corporation of New York

Filed May 16, 1957, Ser. No. 659,619

1 Claim. (Cl. 20—35)

The present invention relates to hatch plugs, or the like.

It is a general object of the invention to provide a hatch plug for a railway refrigerator car, or the like, that is of improved construction having an exceedingly low coefficient of heat transfer and that is of strong and integral construction.

Another object of the invention is to provide a hatch plug of improved composite construction that is exceedingly strong, although of very light weight, and having a very low coefficient of heat transfer.

A further object of the invention is to provide an improved composite hatch plug, wherein a unitary and integral construction is provided that involves a layer of synthetic organic resin that is molded in situ with respect to the other elements thereof.

A still further object of the invention is to provide an improved hatch plug that involves a foamed layer of polyurethane bonding together the other elements of the hatch plug that are also formed of rigid molded structure and of plastic material.

Further features of the invention pertain to the particular arrangement of the elements of the hatch plug, whereby the above-outlined and additional operating features thereof are attained.

The invention, both as to its organization and method of operation, together with further objects and advantages thereof, will best be understood by reference to the following specification taken in connection with the accompanying drawing, in which:

Figure 1 is a fragmentary plan view of a portion of the roof sheet of a railway refrigerator car provided with a hatch frame and carrying a hatch plug embodying the present invention;

Fig. 2 is an enlarged fragmentary lateral sectional view of the roof sheet and the hatch plug, taken in the direction of the arrows along the offset line 2—2 in Fig. 1;

Fig. 3 is a further enlarged fragmentary sectional view, similar to Fig. 2, of certain elements of the hatch plug, indicating the mode of assembly thereof; and

Fig. 4 is a further enlarged fragmentary lateral sectional view similar to Fig. 2, of a modified form of the hatch plug.

Referring now to Figs. 1 to 3, inclusive, of the drawing, a fragmentary portion of a railway refrigerator car 10 is there illustrated that comprises a steel roof sheet 11 having a hatch frame 12 formed therein and surrounding an associated hatch opening 13 formed therethrough, and carrying a hatch plug 14 embodying the features of the present invention. More particularly, the hatch frame 12 may be substantially rectangular in plan and is preferably formed integrally with the roof sheet 11 and disposed about the perimeter of the substantially rectangular hatch opening 13.

The hatch plug 14 comprises complementary outer and inner sections 15 and 16 of rigid molded structure and preferably formed of synthetic organic resin rein-

2

forced with glass fibers, such, for example, as a suitable polyester; and specifically the sections 15 and 16 may be molded from a suitable polyester resin reinforced with glass fibers and having the usual high impact strength.

5 The inner or lower section 16 has a substantially dish-like or pan-like configuration that is substantially rectangular in plan and includes a bottom wall 16a, an upwardly and outwardly directed marginal or boundary wall 16b, and an upwardly and outwardly directed and flared boundary rim or flange 16c; whereby the section 16 is of one-piece molded integral construction. The outer or upper section 15 has a substantially inverted dish-like configuration that is substantially rectangular in plan and includes a top wall 15a and a downwardly and outwardly directed and flared boundary rim or flange 15b; whereby the section 15 is of one-piece molded integral construction.

Suitable flutes or ribs, not shown, may be produced in the sections 15 and 16 in a well-known manner incident to molding thereof for the purpose of lending additional stiffness and rigidity thereto.

The upper and lower sections 15 and 16 are arranged in assembled relation, whereby a substantial cavity was initially formed therebetween; which cavity is substantially completely filled with a self-supporting heat-insulating body arranged between the sections 15 and 16 and intimately bonded thereto. The body mentioned includes a central core element 17 and a surrounding and embedding shell section 18. More particularly, the core

25 section 17 is formed essentially of synthetic organic resin of cellular structure and having a high compressive strength, a high tensile strength and a high impact strength; and preferably the core 17 comprises a pre-formed slab or block of material of rigid cellular structure, such, for example, as a suitable foamed synthetic organic resin, such as foamed polystyrene. More particularly, the shell section 18 is formed essentially of synthetic organic resin of cellular structure and having a high compressive strength, a high tensile strength and

30 high impact strength, and preferably the shell section 18 comprises an in situ formed body of foamed polyurethane resin, such for example, as a polyester group cross-linked with urethane groups. In the arrangement, the core element 17 is entirely embedded in the shell 35 section 18 that is intimately bonded thereto; and also the shell section 18 is intimately bonded to the sections 15 and 16 to retain the elements in assembled relation and to provide a unified integral construction.

The roof of the car 10 comprises an upstanding longitudinally extending roof cap 19 formed of steel and joining together the abutting upturned edge flanges of the oppositely disposed roof sheets 11; which roof cap 19 carries a pair of longitudinally spaced-apart hinges 20 to which the hatch plug 14 is secured for pivotal movement into and out of the hatch frame 12 and respectively into closed and open positions with respect to the hatch opening 13. In the arrangement, a substantially rectangular sealing gasket 14a formed of molded rubber, or the like, is suitably secured to the lower surface of the flared boundary flange 16c of the lower section 16 and positioned to cooperate with the associated hatch frame 12, so as to seal the hatch opening 13 when the hatch plug 14 occupies its closed position.

Each of the hinges 20 comprises a pair of complementary hinge elements 21 and 22 secured together by an associated pintle 23, the hinge element 21 being detachably secured to the hatch plug 14. In the arrangement, the hinge elements 21 and 22 may also be formed of rigid molded material, such, for example, as fiber glass reinforced polystyrene, although it is preferable that the hinge elements 21 and 22 be formed of steel. The hinge element 22 is detachably secured to the hatch plug

14 by a pair of J-bolts 24 and cooperating nuts 25 and by a bolt 26 and a cooperating nut 27. In the arrangement, the hooks of the J-bolts 24 are disposed between the sections 15 and 16 and firmly anchored and embedded in place in the molded shell 18, while the stems thereof project through cooperating holes provided in the top wall 15a of the upper section 15 to the exterior of the hatch plug 14. The stems of the J-bolts 24 further extend through cooperating holes provided in the hinge section 22 and receive the nuts 25 on the outer ends thereof for the purpose of clamping the hinge section 22 in place and to the hatch plug 14. The shank of the bolt 26 extends through aligned openings formed in the marginal flange 16b of the upper section 15 and through the hinge section 22 so that the outer end thereof carries the nut 27 for the securing purpose. Accordingly, it will be understood that the hatch plug 14 is detachably secured to the hinge sections 22 of the pair of hinges 20, thereby accommodating placement and removal of the hatch plug 14 with respect to the pair of hinges 20, as required.

The hatch plug 14 also carries a pair of longitudinally spaced-apart upstanding stops or bumpers 28 that are suitably detachably secured thereto by cooperating J-bolts 29 carrying nuts 30 on the outer ends thereof; the J-bolts 29 also being embedded in the molded shell 18 in the manner of the J-bolts 24, as previously described. Further, the hatch plug 14 carries a lock 31 and a lifting handle 32; which elements 31 and 32 may be detachably secured to the hatch plug 14 in the general manner of the stops 28 and the hinges 20, as described above.

Accordingly, the hatch plug 14 is of sandwich construction that is exceedingly strong and has an exceedingly low heat transfer factor; and moreover, the hatch plug 14 is of very light weight so that it may be readily moved in a simple manner between its open and closed positions with respect to the hatch opening 13 utilizing the handle 32.

In manufacturing the hatch plug 14, the upper and lower sections 15 and 16 are separately molded, in the usual manner; and at this time, a number of holes 16d may be formed in the bottom wall 16a of the lower section 16, as illustrated in Fig. 3. After molding of the upper section 15, the various J-bolts 24 are assembled with respect to the cooperating holes provided in the top wall 15a thereof and secured in place employing the cooperating nuts 25, as illustrated in Fig. 3. Also the J-bolts 29, etc., are assembled with respect to the upper section 15, in a similar manner. The preformed foamed core 17 is provided that is so constructed that it may be readily enclosed in the cavity defined in the lower section 15 and filling a major portion of the volume thereof. In this connection, it is mentioned that the core 17 may be cut from a commercially produced slab of foamed polystyrene, as the exact size and the particular shape of the core 17 are not critical, since it is employed fundamentally to fill the space that must otherwise be filled by the more expensive polyurethane shell 18. At this time, the core 17 is arranged in the lower section 16, and the upper section 15 is assembled upon the marginal flange 16c of the lower section 16 and suitably retained in place. For example, the marginal flange 16c of the lower section 16 may be suitably cemented to the adjacent undersurface of the top wall 15a of the upper section 15 employing an appropriate phenolic cement. At this time, the core 17 fills a major portion of the void or cavity disposed between the sections 15 and 16; and preferably small notches or recesses 17a are formed in the surface of the core 17 disposed adjacent to the upper section 15; which notches 17a are adapted to receive the hooks of the J-bolts 24 and 29, as indicated in Fig. 3. The assembly is then inverted with respect to its position of Fig. 3, so that the core 17 is substantially centrally positioned between the sections 15 and 16, the core 17 being temporarily restrained in position by the cooperation between the hooks

of the J-bolts 24 and 29 and the engaged notches 17a; whereby a shell-like void surrounds the core 17 adjacent to the sections 15 and 16.

At this time, the foamed molding material that is productive of the polyurethane resin upon curing is injected under pressure through one of the holes 16d formed in the bottom wall 16a of the section 16 into the space disposed about the core element 17 and between the sections 15 and 16 so as substantially completely to fill the space mentioned, with the result that the core 17 and the hooks of the J-bolts 24 and 29 are completely embedded in the molding material that is ultimately productive upon curing of the foamed polyurethane shell section 18, the unitary structure is produced, the shell section 18 being intimately bonded to the core element 17 and to the sections 15 and 16 and to the J-bolts 24 and 29. At this time, the several holes 16d formed in the bottom wall 16a of the section 16 may be plugged up with a suitable synthetic organic resin, such as a polyester reinforced with glass fibers, as indicated at 16e, in Fig. 2. Then, the nuts 25, 30, etc., carried by the outer ends of the J-bolts 24 and 29 may be removed in order to facilitate securing of the bumpers 28, etc., to the finished hatch plug 14.

Reconsidering the molding of the polyurethane shell section 18, it is pointed out that a large variety of molding materials may be employed, as the system is predicated upon the reaction of polyisocyanate and water to liberate carbon dioxide, while simultaneously the polymerization and cross-linking reactions between the polyisocyanate and the polyester entrap the liberated carbon dioxide; whereby no external blow or foaming agent is required. Moreover, the resin is self-curing, since the reactions are exothermic and take place at room temperature. When the ingredients are mixed employing some water, the reactions are initiated producing the carbon dioxide gas and the resulting foam; however, suitable catalysts (amines) are ordinarily added to the ingredients to accelerate the reactions and to reduce the curing time. For example, the curing time of a typical molding material can be reduced from about ten hours to about one to two hours by the addition of an appropriate amount of urea. Also the polyesters (alkyd resins) and the polyisocyanates should be selected so as to control the density of the resulting polyurethane resin, as a rigid (or at least a semi-rigid) foamed structure is desired in the present case. Fortunately, the density of the polyurethane resin may be controlled over a wide range from about 1.5 to about 40 lbs./cu. ft. by controlling the amount of water employed, the amount of catalyst added, and particularly by selecting the polyisocyanate used for cross-linking; and in general, it is noted that the diisocyanates produce linear polymers of relatively low density and rigidity, while the triisocyanates and higher polyisocyanates produce more highly cross-linked polymers of relatively high density and rigidity. In the present case, a suitable polyurethane resin (condensation product) may be produced that is formed essentially of copolymers of adipic acid and glycerol cross-linked with naphthylidisiocyanate and some diphenoltriisocyanate.

These polyurethane resins are highly desirable in the present case because of the great compressive strength, the high tensile strength, the high impact resistant characteristic, and the exceedingly low heat transfer factor thereof, together with the circumstance that they are self-curing at room temperature and may be readily molded in situ, so as substantially completely to fill all of the space into which the foamed molding material is injected. Moreover, these resins being of the thermosetting type can withstand temperatures up to 350° F., without damage thereto, which gives ample margin for any high-temperature conditions that may be encountered by the hatch plug, when the refrigerator car is in daytime use in certain desert areas of this country in the summer

months. Furthermore, these resins possess the peculiar characteristic of forming tenacious bonds with almost any kind of material in contact therewith during the curing reactions, and including steel, wood, other resins, etc.

Referring now to Fig. 4, a modified form of the hatch plug 114 is illustrated that is fundamentally of the construction and arrangement of the hatch plug 14, previously described, and including the corresponding parts 115, 116, 117 and 118. In this construction, the upwardly and outwardly directed boundary flange 116c of the section 116 is provided with the extension or rim flange 116f that extends outwardly and downwardly therefrom and having a configuration matching that of the rim flange 115b provided on the section 115; whereby the composite flange disposed about the boundary of the hatch plug 114, when the sections 115 and 116 are secured together, is of double-wall construction, as illustrated. This arrangement provides a very strong composite flange about the hatch plug 114, insuring adequate support thereof by the associated hinges, not shown.

Also in construction, a number of the holes for receiving the molding material of which the shell section 118 is produced are formed in the flange 116c of the section 116, instead of in the bottom wall, not shown, thereof; which holes mentioned are subsequently closed with the plugs, indicated at 116c. Because of this relocation of the holes mentioned, the foamed molding material that is productive of the shell section 118 may be injected into the assembly, in the manufacture of the hatch plug 114, while the assembly is arranged in an upright position. More particularly, the foamed molding material is injected through one or more of the holes mentioned into the space defined between the sections 115 and 116 and surrounding the core sections 117 so as to effect the production of the shell section 118 in the manner previously described.

The remainder of the construction of the hatch plug 114 and the method of making the same are substantially the same as these corresponding items described in conjunction with the hatch plug 14 and are not reiterated in the interest of brevity.

In view of the foregoing, it is apparent that there has been provided a hatch plug for a refrigerator car, or the like, of improved construction and arrangement that is of unitary sandwich construction, exceedingly strong, of light weight and characterized by an exceedingly low heat transfer factor.

While there has been described what is at present considered to be the preferred embodiment of the invention, it will be understood that various modifications may be made therein, and it is intended to cover in the appended claim all such modifications as fall within the true spirit and scope of the invention.

What is claimed is:

A hatch plug for a refrigerator car roof, comprising complementary outer and inner sections, said inner section having a substantially pan-like configuration and including a boundary wall carrying an out-turned marginal rim, said outer section having a substantially cover-like configuration and including an out-turned marginal rim, said sections being arranged in assembled facing relation and defining a cavity therebetween and with the rim of said inner section engaging said outer section and with the rim of said outer section embracing the rim of said inner section, the rims of said sections cooperating with each other to provide a composite flange surrounding said hatch plug and adapted to carry a sealing gasket for cooperation with the associated car roof, each of said sections being of rigid molded structure and formed essentially of synthetic organic resin and having a high impact strength, a self-supporting heat-insulating body arranged between said sections and substantially completely filling said cavity and securing said sections together in assembled relation, said body being of composite construction including an inner core element and an outer shell element intimately bonded thereto, said shell element also being intimately bonded to said sections, said inner core element having high tensile strength and being formed essentially of foamed polystyrene and said outer shell element having high tensile strength and being formed essentially of foamed synthetic organic resin including polyurethane, and a pair of spaced-apart securing devices respectively arranged in a pair of spaced-apart holes provided in said outer section, the inner ends of said securing devices projecting inwardly from said outer section into said cavity and being so embedded in the outer shell element that the outer shell element bonds said inner ends of the securing devices to the inner core element and the outer section, the outer ends of said securing devices projecting outwardly from said outer section and being adapted to be respectively secured to a pair of spaced-apart hinges carried by the associated car roof.
